UNITED STATES PATENT OFFICE.

EDGAR P. ELZEY, OF PARKERSBURG, WEST VIRGINIA, ASSIGNOR TO THE AU-TO PLAY GOODS COMPANY, OF PARKERSBURG, WEST VIRGINIA, A CORPORATION OF WEST VIRGINIA.

CHILD'S CAR OR VEHICLE.

1,302,335.

Specification of Letters Patent. Patented Apr. 29, 1919.

Application filed August 19, 1918. Serial No. 250,562.

To all whom it may concern:

Be it known that I, EDGAR P. ELZEY, a citizen of the United States of America, and resident of Parkersburg, Wood county, State 5 of West Virginia, have invented certain new and useful Improvements in Children's Cars or Vehicles, of which the following is a specification.

This invention involves certain improvements in children's cars or vehicles; and the 10 objects and nature of the invention will be readily understood by those skilled in the art in the light of the following description of the accompanying drawings illustrating 15 what I now believe to be the preferred mechanical expression or embodiment of my invention from among other forms, constructions and arrangements within the spirit and scope thereof.

20 An object of the invention is to improve and simplify the construction of such cars or vehicles that are propelled by the feet of the children seated thereon, or that are used for coasting, with the ends in view of 25 rendering such cars easy to steer, safe in operation, strong and durable in construction, easy to repair, and to overcome the tendency of most cars of this type to lean or tilt laterally or sidewise.

30 A further object of the invention involves improvements in the steering heads of cars of this type and the manner of coupling the car running gear thereto.

With these and other objects in view my 35 invention consists in certain novel features in construction, and in combinations and arrangements as more fully and particularly set forth and specified hereinafter.

Referring to the accompanying drawings: 40 Figure 1, is a side elevation.

Fig. 2, is a front elevation of the steering head.

Fig. 3, is a top plan of the car.

Fig. 4, is a rear elevation of the car, the 45 upper portion of the steering head being broken away.

Figs. 5, 6, and 7, are detail views showing various toys mounted in the opening in the steering head.

50 In the particular example illustrated, the main supporting frame or member of the vehicle consists of a longitudinal plank 1 arranged on edge and at its front end coupled to the steering head and at its rear end 55 coupled to the rear axle. This plank forms

the coupler or reach bar of the vehicle and directly supports the seat board 2 which rests on the top edge thereof and is suitably fixed thereto. This seat is horizontal and arranged longitudinally of the coupler and 60 can be of any suitable form and construction, although as shown it consists of a board having a centrally reduced front end to be straddled by the child when seated on the board. 65

The rear end of the vehicle is supported by a metal axle 3, on the projecting ends of which the two wheels 4, are mounted.

A wooden bolster 5 is mounted on the axle and the central under portion of the bolster 70 is reduced or cut away to expose the central portion of the axle.

The coupler is located a distance above the bolster and is supported thereby and held spaced therefrom through the medium of a 75 cross brace or bar 6 and vertical posts 7. The cross bar rests against the under surface of the seat and traverses the rear end thereof and is suitably secured thereto, while the rear upper corner of the rear end of the 80 coupler 1, is notched or cut out at 8 to receive the cross bar to which it is preferably secured midway between the ends of said bar. I show a pair of the posts 7 and these posts are vertical and spaced a distance apart 85 and fixed to the end portions of the cross bar and bolster. For instance, the upper ends of the posts can be fixed in vertical holes bored in the end portions of the cross bar while the lower ends of the posts can be 90 fixed in vertical holes bored in the end portions of the bolster, so that the cross bar, posts and bolster form a rigid frame of fixedly united parts. This frame can be braced and rendered rigid with respect to 95 the coupler 1 by an inclined metal brace 9 at its elevated front end fixed to the lower intermediate portion of the coupler and at its depressed rear end fixed to the central portion of the axle structure, preferably to the 100 bolster by one or more screws 10 or the like.

The seat board is fixed to the coupler, and the cross bar 6 is fixed to the seat board and preferably to the coupler, and the brace 9 extends down from the coupler to the rear 105 axle while the posts 7 are fixed to the cross bar and bolster. A most strong structure is thus produced.

The front fork or steering head consists of a vertical approximately oblong wooden 110

- plank or bar 11 longitudinally slotted at its lower end to receive the front wheel 12 which is mounted on transverse pin or axle 13 extending transversely through the lower slotted end of the bar and if so desired headed at its opposite ends to brace said bar against splitting. If so desired washers 14 can be arranged on the axle between the wheel and the adjoining edges of the bar.
- 10 The upper end of the bar 11 is preferably reduced in width and concaved at its upper end face to receive the center of the transverse handle bar 15 which is rigidly fixed and secured to the head 11 in any suitable manner, as by vertical bolt or bolts 16 extending down transversely through the handle bar and extending a suitable distance into and longitudinally of the head wherein such bolt can be anchored by nut 17 on the lower end of the bolt and located in a hole bored from front to rear or otherwise through the thickness of the plank forming the head.

The head is arranged in advance of the front end of the coupler 1 and a suitable hinge, king or coupling pin connection is established between said head and the front end of said coupler. For instance, in the example illustrated I show parallel rearwardly projecting upper and lower wooden coupling pin bearing blocks 18 fitting the rear flat face of the head and rigidly secured thereto by bolts or headed rivets 19 extending through said blocks and the head.

35 The front end of the coupler 1 extends forwardly between these two blocks, and is equipped with a vertical hinge, coupling or king pin 20 mounted in aligned vertical holes or bearing openings in the blocks preferably so that the vertical axis of the hinge connection thus established is spaced rearwardly from the rear face of the steering head and is parallel with the longitudinal axis of said head. The said coupling pin 40 is preferably formed of wood of greater length than the vertical width of the plank forming coupler 1 so that the ends of the pin project upwardly and downwardly to extend through the bearing blocks 18. The 45 pin is fitted in the concaved vertical front edge of the coupler and is rigidly secured to said coupler in any suitable manner, as by bolts 21 extending through the pin and rearwardly in and longitudinally of the coupler in which they are anchored in any suitable manner as by nuts 22 located in holes bored transversely through the coupler.

In view of the width of the plank used 60 to form the steering head I prefer to brace and strengthen the same against warping and splitting by headed rivets 23 extending throughout the width thereof from edge to edge and arranged at suitable intervals between the slot receiving the wheel and the

reduced upper end of the head, these rivets fitting in holes bored through said head while washers are arranged between the exterior ends of the rivets and the edges of the board forming the steering head. However, I do not wish to so limit my invention.

By thus forming the steering head or fork of a comparatively wide thick wooden plank I not only gain strength and durability and am enabled to employ the peculiarly advantageous hinge pin coupling between the coupler and head, but I am also enabled to utilize said head to carry and support various objects of interest to the child, such as toys, at a position in front of and easily accessible to the child on the seat. For instance, there is ample length and width of plank between the upper bearing block 18 and the reduced upper end of the head for the formation of a central vertical slot to receive and permit fastening the representation of a horse head 25 cut from a wooden board and at its rear end fitted and secured in said slot. If so desired, an opening 26 can be cut in said portion of the head and a bell 27 can be hung therein from one of the rivets 23, or a toy gun 28, might be arranged in said opening and mounted on a rivet 23 to swing vertically as indicated by dotted lines. A 95 flash light 29 might be mounted in such opening by suitable means so that said light can be swung to forwardly projecting horizontal position or to normal inactive vertical position. I have more or less diagrammatically indicated some among other toys that might be mounted in the head and in front of the child, the essential point of this feature of my invention being the presence of the opening in the head to receive any suitable toy at such position.

I gain advantages by forming the steering head or fork of one piece of material i. e. in this instance by a wooden plank; and by arranging the steering head in advance of the coupler and the seat board; and I also provide a strong support and gain easy steering and control by providing the coupling pin and block connection between the steering head and coupler; and I 110 also gain strength and durability by the peculiar structure between the rear axle and coupler and seatboard, and in this connection it will be noted that the open space between the posts 7 affords the child room 115 for either foot, or in fact both feet, when coasting. In other words the child can stand on the bolster, with his feet between the posts, and can grasp the handle bar when coasting. Also, the child can rest one 120 foot on the bolster while grasping the handle bar, and propelling the car by contacting the pavement with his other foot.

It is evident that various changes, modifications and variations might be resorted 130

to, that features might be left off or other features added, without departing from the spirit and scope of the invention, and hence I do not wish to limit myself to the exact 5 disclosures hereof.

What I claim is:—

1. A child's vehicle comprising a coupler, a seat board fixed thereon, said coupler notched at its upper rear corner, a cross bar 10 in said notch and against the under side of the seat board, a bolster provided with a wheeled axle, and vertical supporting posts at their lower ends fixed to the end portions of the bolster and at their upper ends fixed 15 to the end portion of the cross bar.
2. A child's vehicle comprising a longitudinal coupler composed of a plank set on edge, a longitudinal horizontal seat board on the top edge of said coupler and secured 20 thereto, said coupler projecting forwardly in advance of said board, a rear wheeled support for said coupler and plank embodying fixed vertical posts spaced apart so that the child can place his feet between the posts 25 when coasting, and a wheeled front steering head supporting and pivotally coupled to the front end of said coupler.
3. A child's car comprising a plank arranged on edge and forming the longitudinal 30 coupler of the car, a horizontal seat board on the top edge of said plank and fixed thereto, a vertical front wheeled steering head arranged in advance of said board and plank and having pivotal supporting 35 connection with the front end of the plank, and a rear wheeled support, embodying spaced supporting uprights and a foot rest between said uprights.
4. A child's car embodying a longitudinal 40 body providing a seat; a rear wheeled support for said body comprising spaced uprights at their upper ends fixed to said body, a foot rest between the lower ends of said uprights, and an upwardly and forwardly extending brace at its front upper end secured 45 to the body and at its lower rear end secured to said wheeled support; a vertical wheeled front steering head in advance of said body; and a body-supporting pivotal connection 50 between the front end of said body and said head.
5. A child's car comprising a body provided with a seat and having a straight forwardly projecting front end with a vertically elongated front edge forming a verti- 55
- cal seat, a vertical pin fitting said seat and having upwardly and downwardly projecting ends, means rigidly fixing said pin in said seat and to the body, a vertical wheeled front steering head in advance of the body 60 and having fixed bearing members projecting rearwardly from its rear face above and below the front end of the body and loosely receiving said ends of the fixed pin, and a rear wheeled support for the body. 65
6. A child's car comprising a body embodying a longitudinal plank arranged on edge and projecting forwardly, a vertical pin fixed to the vertical front edge of said plank and having projecting ends, bolts fixing said pin and extending into said plank, nuts in the plank anchoring the bolts, a wheeled front steering head supporting the front end of the body and having means loosely receiving said pin ends, and a 70 wheeled support for the rear end of said body. 75
7. A child's car comprising a body having a wheeled rear support, and a front wheeled steering head having pivotal body-supporting connection with the front of the body, said head embodying an upright plank having a cross handle fitting the top edge thereof, a securing bolt for said handle extending longitudinally into the plank, and a nut 80 in the plank receiving and anchoring said bolt, substantially as described. 85
8. A child's car comprising a body having a seat and a rear wheeled support, a vertical wheeled front steering head having pivotal connection with the body, said head embodying a plank having a top handle and between the pivotal connection and handle formed with a transverse opening in front of said seat, and a toy carried by said head 90 at said opening, substantially as described. 95
9. A child's car comprising a body having a wheeled support, and a front wheeled steering head arranged in front of said body and having pivotal supporting connection 100 therewith, said head embodying an upright plank having a handle at its upper end and a rod extending through the plank between the handle and pivotal connection, said plank having an opening extending forwardly therethrough adjacent to said rod, and a toy arranged in said opening and movably supported by said plank. 105
